UNITED STATES PATENT OFFICE.

EARL W. LESHER, OF CLEVELAND, OHIO.

OUTFIT FOR POLISHING SHOES.

1,129,580.

Specification of Letters Patent. Patented Feb. 23, 1915.

Application filed June 17, 1914. Serial No. 845,618.

To all whom it may concern:

Be it known that I, EARL W. LESHER, a citizen of the United States, and resident of Cleveland, in the county of Cuyahoga and State of Ohio, have invented certain new and useful Improvements in Outfits for Polishing Shoes, of which I hereby declare the following to be a full, clear, and exact description, such as will enable others skilled in the art to which it appertains to make and use the same.

The invention has reference to a neat, convenient and portable shoe polishing apparatus in which the essential parts, the brush, the dauber and the box of paste or shoe polish are assembled together into one convenient article ready at any time for immediate use. This construction also prevents the separate portions from becoming mislaid and scattered apart.

The invention comprises a polishing brush having a heavy back, provided with openings in which the box of polish and daubing tool are detachably retained, and also has reference to the mechanism for retaining these portions of the apparatus in place.

The invention further comprises the combination and arrangement of parts and construction of details hereinafter described shown in the accompanying drawings and specifically pointed out in the claims.

In the accompanying drawings Figure 1 is a plan view of the device; Fig. 2 is a longitudinal section through the assembled parts; Fig. 3 is an end elevation; Fig. 4 is a perspective view; Fig. 5 is a perspective view of a modification thereof; Fig. 6 is a perspective view of preferred retaining means for the polish box and cover.

In these views A is a polishing brush, having a solid back a. B is a box of polish which is detachably secured in an opening C, preferably positioned at one end of the back a. This opening has an extension a' through the edge of the back. D is the daubing tool which may be of felt or bristles or any suitable material and is provided with a back d, and a handle d', inserted therein.

The dauber is inserted in an opening E in the back a, and is detachably retained therein by means of a spring member E'. The handle d' lies conveniently upon the surface of the back where it can be readily seen. By rotating the handle it can be made

to project beyond the side of the brush so that it can be readily grasped by the hand.

When the dauber is formed of bristles a narrow rubber band d³ can be slipped over the bristles in an unsightly manner and also closing them together so that they can be introduced into the opening easily.

The box of polish B is provided with a flange B² which is engaged by a catch B³ upon a metal band or plate B⁴ and retained in its place. The opposite edge of the box of polish is engaged by a similar catch B⁸ or projection from the wall of the opening.

The cover B' of the box of polish is provided with a flange B⁵ and means are shown for detaching the cover by raising the flange without disturbing the box in its seat in the back. Two ways of performing this action are shown. In Figs. 1, 2, 3, 4, and 6, a lever F pivoted upon the metal band B⁴ is shown, while in Fig. 5 a cover lifting member is shown secured to the dauber and rotatable therewith. This lever is provided with a catch B⁶ which engages the flange on the cover and with a finger plate B⁷ by means of which it is depressed. This lever could be rotatably attached in any other desired manner in the back a.

In Fig. 5 a wedge shaped edge G is raised upon a plate G' which is attached to the underside of the dauber. This wedge shape edge is inserted underneath the flange upon the cover when the dauber is rotated to place the handle transversely to the back a to release the dauber. The cover of the polish box will then be lifted simultaneously with the movement of the dauber.

The thin edge of the wedge upon the dauber will be preferably always in engagement with the flange of the cover and since the covers of polish boxes are made very tight to prevent evaporation of the contents, the cover will assist in retaining the dauber in place.

In assembling the parts the edge of the box is first inserted underneath the spring catch B³ and then the opposite edge of the box is pressed down until the catch B⁸ passes over the flange B² on the box.

The lever which removes the cover is accessible through the extension a' of the opening.

Having described the invention what I claim as new and desire to secure by Letters Patent is:

1. The combination with a support having an opening adapted to receive a closure having a lid, said lid having a marginal flange, and said box having a corresponding flange spaced from the flange on said lid when the box is closed, of a metal retaining device in said opening, engaging opposite sides of the flange on said box, and a lever pivoted upon said metal retaining device, and having a projection inserted between said flanges when said box is closed, said lever rotatable on its pivot to engage said upper flange so as to remove said cover. 45
5. In a shoe polishing outfit, a support, said support provided with an opening adapted to receive a box of polish, a spring retaining plate in said opening for said box, and a lever mounted upon said retaining plate, 50 said lever having a catch engaging the cover of said box.
6. In a shoe polishing outfit, in combination, a support, said support having an opening for inclosing a box, a box in said 55 opening and a cover therefor removable when one edge has been raised, said box and cover having each a circumferential flange, said flanges spaced apart, means for detachably retaining said box in said opening, 60 said box retaining means engaging said flanges, and a rotatable lever pivoted adjacent to said box and cover, and interengaging said respective flanges whereby by rotating said lever said cover can be removed. 65
7. In a shoe polishing outfit, in combination, a support having an opening, a polish box and air tight raisable cover therefor, 70 said box and cover provided with corresponding parallel spaced circumferential box retaining and cover raising flanges, and a lever pivoted adjacent to said box and cover, said lever intermediate of said flanges, whereby by the rotation of said lever said 75 cover can be removed substantially as described.
3. In a shoe polishing outfit, in combination, a support, said support containing an opening, a device in said opening for removably retaining a box of polish therein, and a separate rotatable cover detaching device mounted on said box retaining device, and adapted to elevate one edge of said cover.
4. In a shoe polishing outfit, a support, a spring plate mounted upon said support and having retaining edges underneath which the edges of a box of polish are secured, and a separate device engaging with the cover of said box for detaching said cover from said

In testimony whereof, I hereunto set my hand this fifteenth day of June 1914.

EARL W. LESHER.

In presence of—

AUGUSTUS W. BELL,
Wm. M. MONROE.
